UNITED STATES PATENT OFFICE.

ROBERT ALLEN, OF CAVERSHAM, ENGLAND.

STEAM-SUPERHEATER.

1,262,428.

Specification of Letters Patent.

Patented Apr. 9, 1918.

Original application filed July 2, 1913, Serial No. 777,049. Divided and this application filed December 30, 1915. Serial No. 69,458.

To all whom it may concern:

Be it known that I, ROBERT ALLEN, a subject of the King of Great Britain and Ireland, residing at "Lynwood", Kidmore Road, 5 Caversham, Oxfordshire, England, have invented certain new and useful Improvements in Steam-Superheaters, of which the following is a specification.

This invention relates to a tubular steam 10 superheater for locomotive, marine, and other boilers, and is a division of application Serial No. 777,049, filed July 2, 1913. The object of the invention is to provide for the ready removal of soot or other material 15 from the interior of the superheating tubes to facilitate the transmission of heat from the combustion gases to the steam and generally to provide an efficient superheater of simple construction which can be conveniently fitted into the smoke boxes of locomotives and other smoke-tube boilers.

Another object of the invention is to provide for the greatest possible contact between the steam and the superheating tubes 25 during the travel of the steam from the inlet to the outlet of the apparatus, and also to so arrange that the steam coming from the boiler shall be admitted to the superheater at that point from which the heating gases 30 are expelled and, traveling through the apparatus, shall leave same at or near the point of admission of the hot gases from the boiler tubes, thereby securing the maximum heating effect.

According to this invention, tubes, preferably provided with coincident internal and external spiral ribs formed solid with the tubes or welded or soldered to the tubes as described in British Patent No. 15,574/12, 35 are arranged horizontally in boxes or casings provided with baffles and constructed to facilitate the admission of steam to the tubes for cleaning them.

The invention is hereinafter described 45 with reference to the accompanying drawings in which,

Figures 1 and 2 are sectional front and sectional side elevations respectively of a superheater constructed according to this 50 invention.

As shown, superheating tubes *a* formed with internal and external helical ribs *b* are fitted horizontally in casings, divided vertically into two units *c* of box section, each

having tubes *a* passing through them, separate apparatus each composed of two units being provided for each cylinder.

One of these units is provided with an extended side which corresponds and makes joint with the side of the other unit, thus forming, between the two units, an inclosed steamtight space *h*.

Similarly as shown at *a* Fig. 2 the tubes *a* of one unit extend through and beyond the back, the same distance as the extended side above mentioned; and these extended tubes being in register with the corresponding tubes in the other unit or units, make joint with them and form a continuous tube through both the units. The entire apparatus is, in the case of a locomotive, fixed in the smoke box in suitable relative position to the fire tubes.

In the front unit, that is the unit farthest from the smoke tube plate, baffles are arranged in the form of thin sheet metal partitions *i* so disposed as to group the superheating tubes into a continuous path, along which the steam is compelled to pass in such a manner as to increase the contact of 70 the steam with the heating tubes to the maximum available.

The back unit, which is nearest to the boiler tube plate is arranged with similar partitions or baffles *i* shown on the left in Fig. 1, so disposed as to cause the steam to travel from side to side in a path approximately at right angles to the travel through the front unit.

The steam in this way makes a complete 90 circuit of the superheater, being admitted at *e* at the forward end of the front unit, caused to travel several times up and down it to a communicating cross connection *e*, by which it is conducted into the back unit, 95 through which latter it passes, as above described in a circuitous path to the main outlet *j* from the superheater to the cylinder.

In order to provide for the cleaning of the inside of the superheating tubes from any 100 soot or other material deposited, holes *k* are provided in that portion of the tubes which passes through the intermediate steam-tight space *h* between the two units and a suitable connection *l* is arranged for the admission of live steam into the said space, whereby such steam may be blown into the tubes through the holes from time to time as re-

2
quired, and internal cleaning of the tubes thus effected.

Preferably the holes k for so admitting steam into the inside of the heating tubes should be disposed in such a manner as to provide for the admission of steam into each section of the interior of the tube, formed by the internal ribs.

As shown in the right half of Fig. 1 which is a section through the space h , vertical baffle plates or partitions l^1 may be arranged across the intermediate space h between the two units, with a branched steam inlet l^2 communicating with each section of the space so partitioned in order to provide for a more equal distributing of the steam, and thus obviate any restricted path being taken by same and to equalize the cleaning effect. If desired the space described above as intermediate between the two units may be arranged in combination with a single unit. Provision may be also made for the admission of live steam at the bottom as well as the top of the superheater, to increase the cleaning effect.

I do not confine my invention to the combination of two units, as described which may, if necessary, be increased to three or more, and as will be readily understood one such apparatus comprising one or more units may be provided for both cylinders or for each cylinder in the case of locomotive boilers.

By inserting rods in the center of the tubes to close the passage between the ribs the

whole of the gases can be compelled to flow in a helical course through the tubes.

What I claim and desire to secure by Letters Patent is:—

1. A superheater comprising a casing divided into units, tubes passing through each of said units, one of said units having an extended side which makes joint with its cooperating unit forming a steam-tight chamber between them through which said tubes also pass, said tubes having apertures in the portions thereof which pass through said steam-tight chamber, and means for admitting steam to said space.

2. A superheater comprising open-ended tubes for the passage of the hot gases, a casing to which said tubes are fitted and provided with steam inlet and outlet connections, and a separate steam-tight chamber in the casing communicating with the tubes and serving to convey steam to said tubes for cleaning them.

3. A superheater comprising open-ended tubes and separate casings into which said tubes are fitted, each casing with its tubes forming a unit, means connecting said units to provide a steam-tight chamber between them, said chamber communicating with the interior of the tubes through suitable openings and serving to convey steam to the tubes for cleaning them internally.

In testimony whereof I have affixed my signature.

ROBERT ALLEN.
